UNITED STATES PATENT OFFICE.

LEO STEINSCHNEIDER, OF BRUNN-KONIGSFELD, CZECHOSLOVAKIA.

DISTILLING APPARATUS FOR LIQUIDS.

Application filed February 18, 1920. Serial No. 359,515.

To all whom it may concern:

Be it known that LEO STEINSCHNEIDER, engineer, citizen of the Czechoslovakia Republic, residing at Brunn-Konigsfeld, in the 5 Czechoslovakia Republic, has invented certain new and useful Improvements in Distilling Apparatus for Liquids, of which the following is a specification.

In distilling heavy hydro-carbons such as 10 petroleum, lignite-tar, coal tar and the like, for the production of heavy asphalt or solid residues, such as coke, there is usually employed vessels or stills of comparatively large dimensions. The stills are filled with liquid 15 to a certain height and the contents are distilled according to requirements down to asphalt or solid coke. In known distilling apparatuses, great difficulties are met with, particularly in the case of distilling off to 20 solid coke. The coke, in order to be commercially useful, must be thoroughly "gloved", and must contain no asphalt.

When using such stills, the coke at the 25 end of the distillation remains in a thick layer in the boiler, and the thorough "glowing" of the coke is rendered very difficult owing to the thickness of the layer. The boiler becomes red-hot before the top layer of the coke has become free from asphalt, 30 and the boiler is consequently destroyed very quickly. The boiler surface can only partially be used as heating surfaces, because only those parts of the surface that are covered at the end of the distillation with asphalt or coke, may be subjected to the action 35 of the flue gases. A further great drawback when using such distilling boilers is to be found in the fact that the coke can only be drawn when the boiler has become completely cool. As it must be entered for the 40 cleaning purposes, there is danger to the workmen in consequence of the development of gases. The same is also the case when the boiler is being cleaned.

45 The deleterious effects of the flue gases on the walls of such distilling boilers is considerably increased if the distillation is effected under pressure or in a vacuum, and the risk of destruction of the still is considerably greater.

The employment of cylindrical vessels or 50 retorts of comparatively small diameter

will eliminate these defects, as the layer to be heated through or "glowed" is reduced in consequence of the smaller cross section of 55 the retorts. The still, when employed for distillation under pressure or in a vacuum, is also less subject to breakdowns and burning of the walls of the pipes can be avoided more easily in consequence of the thinner 60 layers of liquid or coke. When, however, retorts of ordinary construction are used for the distillation, another serious drawback is met with. If, for instance, a liquid containing, say 20% of coke is to be distilled in a 65 retort, the liquid capacity of the retort must be about five times as great as the volume of the coke. Hence, when the distillation is completed, since only the coke in the retort has to be subjected to the action of the flue 70 gases for "glowing" purposes, at least four fifths of the retort must extend beyond the furnace. In practice this requires retorts which are unduly long and difficult to handle.

75 These drawbacks are obviated if retorts are fitted at the lowest part of a boiler, in such a manner that, according to the material to be distilled, the liquid sinks from the larger upper part or boiler into the retorts 80 so that, at the end of the distillation, the whole retort, or at least the largest part of it, remains under the action of the flue gases.

In certain cases a constructional form of 85 the improved apparatus is preferably used in which each single retort is provided with a boiler-shaped enlargement or extension. Any number of such single retorts may then with advantage be combined in a single furnace or oven. The employment of a boiler 90 of the requisite size with only one retort is sufficient, especially in cases where the raw product to be distilled yields only small quantities of residues, or in cases where only small quantities are treated.

95 In the accompanying drawings:

Figure 1 is a vertical sectional view, and Figure 2 is a horizontal sectional view of one form of an improved apparatus comprising several retorts and a vertically arranged boiler.

100 Figures, 3 and 4 are similar views of a modification employing a horizontal boiler.

Figures 5, 6 and 7 are transverse vertical

sectional, longitudinal vertical sectional and horizontal sectional views, respectively, of further modifications.

Figure 8 is a longitudinal sectional view 5 of a modification of the apparatus.

Figure 9 is a detail view showing means for admitting steam to the retorts.

Fig. 10 is a transverse sectional view of the form shown in Figure 8.

10 Figures 11 to 16 are end and side views of other forms of the invention employing horizontal retorts.

In the embodiment of the invention illustrated in Figs. 1 and 2 *a* is a cylindrical vertical vessel with a cover *b* and gas outlet pipe *c*. At the bottom *d* of the vessel, retorts *e*, having preferably a conical shape, are fixed. These retorts communicate with the interior of the boiler and are closed at 20 their bottom ends by removable covers *f*.

The apparatus, which is surrounded by brick work *g*, is played on by the fire gases that enter at *h* and escape at *i* in such a manner that the contents remaining finally in 25 the retorts *e* reach up to a point *k*, namely up to the brick work of the fire place.

Before the commencement of the distillation the still is filled to a height *l*. The upper part *a* is preferably not exposed during 30 the whole period of distillation to the hottest furnace gases. It may, however, be played on by the gases escaping to the main flue, that may be caused to pass through fire tubes or smoke tubes in the upper boiler.

35 By this arrangement it is possible to obtain large heating surfaces, a large capacity for the still, and suitable dimensions of the upper part of the retort so that at the end of the distillation the contents remaining in 40 the apparatus fill only the retorts on which the fire gases play.

When the distillation is finished, the covers *f* of the retorts *e* which are arranged exteriorly of the hot gas passageway *f²⁰* are 45 opened, and the contents discharged. The cleaning of the retorts can be effected easily from the exterior when the cover *b* is removed.

An example of a constructional form of a 50 distilling boiler with a horizontal upper part is shown in Figs. 3 and 4, in which

a' is a horizontal boiler of the requisite size; *c'* is the gas escape pipe, *e²* and *e¹* are the retorts that are fitted at the lowest point 55 *d'* of the boiler; and *f'* are the removable closing covers of the retorts.

The fire gases enter the fire gas passageway *f¹⁰* which is surrounded by the brick-work *g'* of the apparatus, at *h'* and pass 60 to the chimney in the direction shown by the arrow at *i'*.

When using several retorts, they may be arranged into groups of any desired number of retorts, as is shown for instance, in the 65 case of the retorts *e¹*; or they may be ar-

ranged in any required number in series, as in the constructional example shown for the retorts *e²*.

The cleaning of the retorts after being emptied may be effected from the outside by 70 the provision of openings *m* or, if the boiler is sufficiently large, the openings *m* may be entered for cleaning the boiler from within.

The distilling of the liquid contents is effected (as described with reference to the 75 constructional form shown in Figures 1 and 2), from the liquid level *l'* to the liquid level *k'* in such a manner that at the end of distillation the fire gases play only on the contents of the retort. 80

The boiler *a'* is protected by the brick-work *n* from the direct action of the hottest furnace gases. While the two constructional examples of the apparatus shown will satisfy the demands made on them, the 85 cleaning of the retorts at the end of the distillation is accompanied with certain defects if the boiler dimensions are great, in so far as the boiler must generally be opened and entered for thorough cleaning. 90

This is more particularly open to objection when the coke that has been formed sticks to the sides of the apparatus.

This drawback is obviated in the construction shown by way of example in Figures 5 95 to 7. In the latter figures

a² is the boiler, for example a horizontal cylindrical one, which is filled to *l²* with liquid. At the bottom *d²* of the same, retorts *e²* are fitted by means of lateral connecting branch pipes *e⁴*. These retorts are closed at the bottom by covers *f²* and at the top by covers *f³* so that the retorts may be easily cleaned. 100

The upper parts of the retorts projecting 105 from the brickwork *g²* of the apparatus are protected by lagging *o* against radiation. This lagging is removed when the retorts are emptied and cleaned. The boiler and the lateral branches of the retort are protected 110 by the brickwork *n'* from the action of the hot fire gases. The charge is calculated in such a manner that at the end of distillation the residue remaining in the apparatus remains in the retorts up to *k²*. 115

At the end of the distillation the covers *f²* and *f³* are opened and the contents (coke) of the retorts are pushed from the exterior out through the discharge opening.

In this form the gases enter the fire gas 120 passageway *f¹¹* through the inlet *h²* and travel in a direction indicated by the arrow *i²*.

It will be noted that the covers *f²* and *f³* are arranged exteriorly of the fire passageway *f¹¹*. 125

In order to reduce the cost of repairs to a minimum, the retorts are preferably made in two parts, the upper part of the retort fitted with side connections and cleaning 130

openings, and the lower part of the retort, which is subjected to the action of the fire gases, being detachably connected together (by a flange) which connection in the case of 5 retorts of a conical shape, is provided preferably at the interior end. The place of the connection of the two parts of the retort is preferably so arranged as also to be exteriorly the brickwork, so as not to be exposed 10 to the action of the fire gases.

The use of conical retorts, that widen towards the delivery end, has the great advantage that the pushing out of the coke is made considerably easier.

15 Figures 8, 9 and 10 illustrate a constructional example of the improved apparatus comprising several retorts, each of which is provided with a boiler-like enlargement or extension. In these figures 20 e^3 and e^6 are the retorts, which preferably widen conically towards the bottom, and which at their narrower upper ends, merge into boilers a^3 . Each boiler a^3 can either be made integral with the retort, as is shown in 25 the case of retort e^6 , or be connected with the retort by means of a releasable connection (for instance the flange E) as shown in the case of retort e^5 .

The boiler a^3 is filled with liquid up to b^3 , 30 and the liquid is distilled in the retort down to b^3 .

In the constructional example shown, the flue gases escape from a suitable furnace, from the grate p for instance, pass into a 35 flue q common to all the retorts, and through openings r (preferably provided with chequer brickwork) to the retorts. The amount of the flue gases passed over the several retorts is controlled by regulating 40 dampers s , so as to correspond to the progress of the distillation in each retort.

The products of combustion escape through a common flue z to the chimney. The boilers are preferably protected by the brickwork n^2 45 of the masonry casing g^3 of the boiler, from the direct action of the hottest flue gases.

The liquid is charged into the retorts preferably through a pipe u (which can be closed by means of the valve v) common 50 to all the retorts.

The gases of distillation of all the retorts may pass through pipes x into a common pipe y for the products of distillation, it being possible by means of an appropriate arrangement of valves l for samples to be 55 taken at any time. The pipes x can also convey the vapours of distillation of each retort to separate cooling devices. Valves w , 2 and 3 are provided for shutting off the 60 lines of piping.

After the completion of the distillation the residue remaining in the retorts is discharged from the retorts after opening the covers f^1 .

65 In an apparatus having a common furnace

and comprising several retorts, any one of the retorts that may be become damaged can be shut off by simply closing the valves v and w .

In order that with relatively long retorts 70 the temperature of the liquid to be distilled may be as uniform as possible in the various layers of each retort, during the process of distillation steam is blown into the liquid to be distilled, preferably at the bottom of 75 the retorts, for instance as shown in Figure 9, by means of pipes A fitted preferably at the lowest point of the same, from a common steam supply C through the steam valves B.

The retorts may be arranged vertically 80 as in Figs. 1-10 of the drawings or in any other suitable direction in relation to the boiler as shown by example in the Figs. 11-16, in which the retorts are arranged horizontally.

In Figs. 11-12 the retorts e^7 having covers f^6 are fixed directly to the boiler a^4 and each retort is provided with a cleaning opening m' arranged in a branch pipe of the boiler a^4 which branch pipe is closed by a removable cover f^5 .

In Figures 13 and 14, the retorts e^8 having end covers f^7 are connected to the boiler a^5 by means of branch pipes d^3 to which the retorts are connected by means of lateral pipes.

In Figs. 15-16 the lateral pipe d^4 of each retort e^9 is arranged in the middle of the retort. The contents of the retorts may be pushed out at each end through the discharge openings closed by removable covers f^8 .

Having now particularly described and ascertained the nature of my said invention and in what manner the same is to be performed, I declare that what I claim is:—

1. A distilling and coking apparatus for heavy hydrocarbons comprising a furnace having a fire gas passageway therethrough, a receptacle to receive the hydrocarbons, a retort tube communicating at its upper end with the lower part of the receptacle and extending down through the fire gas passageway, said retort tube being closed to the fire and also closed to the reception of the hydrocarbons except at its upper end, and having a lower end arranged exteriorly of the gas passageway, and a removable cover closing the outer end of said retort tube.

2. A distilling and coking apparatus for 120 heavy hydrocarbons, comprising a furnace having a fire gas passageway, a receptacle to receive the hydrocarbons, a plurality of retort tubes communicating at their upper ends with the lower part of the receptacle 125 and extending down through the fire gas passageway, each of said retort tubes being closed to the reception of hydrocarbons except at their upper end, each of said retort tubes having an outer end extending exte- 130

riorly of the fire gas passageway, and a removable cover closing the open end of each of said tubes.

3. A distilling and coking apparatus for heavy hydrocarbons comprising a furnace having a fire gas passageway therethrough, a plurality of retort tubes extending down through the fire gas passageway, each of said retort tubes being provided with an enlarged head for the reception of the hydrocarbons, said tubes being closed to the fire and also to the reception of the hydrocarbons except through the enlarged heads, the outer ends of said retort tubes extending exteriorly of the gas passageway, and means at the exterior ends of said retort tubes permitting the contents of the tubes to be removed on the exterior of the gas passageway.

4. A distilling and coking apparatus for heavy hydrocarbons comprising a furnace, having a fire gas passageway therethrough, a plurality of retort tubes extending through fire gas passageway, each of said retort tubes being provided with an enlarged head to receive the hydrocarbons, each of said retort tubes being closed to the fire and also closed to the reception of hydrocarbons except at their upper end, the outer end of each of said retort tubes extending exteriorly of the gas passageway, and a common vapor escape pipe connected with the heads of the retorts.

5. A distilling apparatus for liquid hydrocarbons comprising at least one retort tube and a boiler, a fire gas passageway, the retort tube extending through said fire gas passageway and having an outer end arranged exteriorly of the gas passageway, and a removable cover closing the outer end of the retort tube, said retort being of conical shape tapering toward the boiler.

6. A distilling and coking apparatus for hydrocarbons comprising a furnace having a fire gas passageway therethrough, a recep-

tacle to receive the hydrocarbons to be distilled, a retort tube connected at its upper portion with the lower portion of the receptacle, both ends of the retort tube extending exteriorly of the gas passageway and said retort tube being closed to the fire and also to the reception of hydrocarbons except at its upper portion and being provided with removable covers for closing both ends of the retort tube.

7. A distilling apparatus for liquid hydrocarbons comprising the combination with a boiler and a fire gas passageway, of at least one retort tube extending through the fire gas passageway, the said retort tube consisting of two detachably connected parts, the upper part being provided with a cleaning opening having a removable cover and a lateral branch pipe connecting the upper part of the said retort to the lowest portion of the boiler, the point of connection between the retort parts being arranged exteriorly of the passageway.

8. A distilling and coking apparatus for hydrocarbons comprising a furnace having a fire gas passageway extending therethrough, a receptacle above the fire gas passageway for receiving the hydrocarbon, a retort tube connected at its upper portion to the receptacle and extending through the fire gas passageway, said retort tube being closed to the fire and also closed to the reception of hydrocarbons, except at its upper portion, its lower end extending exteriorly of the fire passageway and having a removable cover thereon, and means for introducing steam into the lower part of the retort tube.

In testimony whereof I have affixed my signature in presence of two witnesses.

LEO STEINSCHNEIDER.
